(57) **CLAIM**

The ornamental design for a vehicle rear lower bumper
cover, as shown and described.

DESCRIPTION

FIG. 1 is a front elevational view of a vehicle rear lower bumper cover, showing our new design;
FIG. 2 is a left side elevational view thereof;
FIG. 3 is a right side elevational view thereof;
FIG. 4 is a top plan view thereof;
FIG. 5 is a bottom plan view thereof;
FIG. 6 is a bottom, front and left side perspective view thereof; and,
FIG. 7 is a top, front and left side perspective view thereof. The portions of the bumper cover shown in half tone form
no part of the claimed design.
Any broken lines represent an internal boundary of the
design; the line itself and the area within form no part of the
claim.
